UNITED STATES PATENT OFFICE

JOHN K. HICKS, OF EL PASO, TEXAS

DESIGN FOR BOY'S PANTS

Application filed January 21, 1932. Serial No. 42,586. Term of patent 7 years.

To all whom it may concern:

Be it known that I, JOHN K. HICKS, a citizen of the United States, residing at El Paso, in the county of El Paso and State of Texas, have invented a new, original, and ornamental Design for Boys' Pants, of which the following is a specification, reference being had to the accompanying drawings, forming part thereof:

I claim:—

The ornamental design for a pair of boy's pants, as shown.

JOHN K. HICKS,
